PAGE 3

FIG. 4

FIG.5

FIG.6

FIGURE 1 is a front elevational view of a microfilmer showing my new design;

FIGURE 2 is a rear elevational view thereof;

FIGURE 3 is a top plan view thereof;

FIGURE 4 is a front perspective view thereof;

FIGURE 5 is a side elevational view thereof taken from the right of **FIGURE 1**; and

FIGURE 6 is a side elevational view taken from the left of **FIGURE 1**.

The bottom, not shown, of the microfilmer is conventional and without ornamentation.

I claim:

The ornamental design for a microfilmer, as shown and described.
